SEWING MACHINE CABINET

Robert C. Flynt, Sr., Kernersville, N. C.

Application February 1, 1956, Serial No. 40,000

Term of patent 3½ years

(Cl. D33—12)

I claim:

The ornamental design for a sewing machine cabinet, substantially as shown.
